US00D520959S

(12) **United States Design Patent** (10) **Patent No.:** **US D520,959 S**
(45) **Date of Patent:** **** May 16, 2006**

(54) **VACUUM SWITCH**

(75) Inventors: **Shigekazu Nagai**, Tokyo-to (JP);
Yoshiharu Ito, Toride (JP); **Takashi Toyama**, Moriya (JP)

(73) Assignee: **SMC Kabushiki Kaisha**, Tokyo (JP)

(**) Term: **14 Years**

(21) Appl. No.: **29/206,739**

(22) Filed: **Jun. 1, 2004**

(30) **Foreign Application Priority Data**

Dec. 1, 2003 (JP) 2003-035697

(51) **LOC (8) CI.** **13-03**

(52) **U.S. CI.** **D13/158**

(58) **Field of Classification Search** D13/133,
D13/147, 158, 166; 200/19, 25, 81 R, 83 R,
200/5 R, 52 R; 218/118, 143; 417/19, 182,
417/183, 187
